UNITED STATES PATENT OFFICE.

ELISHA F. HIRST, OF RICHMOND, INDIANA.

ADJUSTABLE WRENCH.

SPECIFICATION forming part of Letters Patent No. 734,329, dated July 21, 1903.

Application filed April 18, 1903. Serial No. 153,228. (No model.)

To all whom it may concern:

Be it known that I, ELISHA F. HIRST, a citizen of the United States, and a resident of Richmond, in the county of Wayne and State 5 of Indiana, have invented a new and Improved Adjustable Wrench, of which the following is a full, clear, and exact description.

The object of this invention is to provide novel and simple details of construction for 10 an adjustable wrench which afford a considerable range of adjustment for the movable jaw of the wrench, adapt said jaw for quick, convenient, and reliable adjustment toward or from the fixed jaw, and provide means 15 for reliably securing the movable jaw at a desired point.

The invention consists in the novel construction and combination of parts, as is hereinafter described, and defined in the appended 20 claims.

Reference is to be had to the accompanying drawings, forming a part of this specification, in which similar characters of reference indicate corresponding parts in all the figures.

25 Figure 1 is a sectional side view of the wrench on the line 1 1 in Fig. 2, showing interior details. Fig. 2 is a transverse sectional view substantially on the line 2 2 in Fig. 1; and Fig. 3 is a sectional side view of the 30 adjustable jaw and of the handle-bar of the wrench, showing modified means for preventing too free a movement of said jaw.

The handle-bar 5 is of suitable length and other dimensions for effective service and is 35 preferably rectangular in cross-section. A grip-piece or handle 6 of proper length may be formed or secured on one end of the handle-bar 5, and at the opposite end a jaw 7 of usual form is provided and fixed thereon, 40 having its gripping-face *a* disposed at a right angle with the adjacent side of the handle-bar.

Upon the handle-bar 5 the sliding jaw 8 is 45 mounted and is provided with its extension 9, wherein a recess *b* is formed. From the jaw 8 a rectangular loop 8^a depends, and a similar loop 9^a is formed on the free end of the extension 9, the loops 8^a 9^a being of such interior form and size as permits them to receive and loosely fit upon the handle-bar 5.

In Fig. 1 a preferred means for restraining the jaw 8 from moving too freely on the han-

dle-bar is shown, consisting of the following details: A stud-bolt 10 is screwed through a threaded perforation formed transversely in 55 the handle-bar 5 and has its head 10^a bedded in a countersunk enlargement of the threaded perforation, which permits the loops 8^a 9^a to slide freely over said bolt-head. The opposite end portion of the stud-bolt 10, which 60 may be smooth, projects into the recess *b*, and upon this end portion of the stud-bolt the looped end of the spiral spring 11 is mounted, the opposite end of said spring being secured upon the inner end of the screw- 65 plug 12, that is screwed into a threaded perforation in the end wall of the jaw extension 9.

It will be seen that when the spring 11 is drawn taut by an adjustment of the screw- 70 plug 12 the tension of said spring will pull the cross-bar of the loop 9^a into close contact with the adjacent side of the handle-bar 5, producing sufficient friction between the loop 75 9^a and handle-bar to prevent the movable jaw 8 from moving along the handle-bar until it is shoved by hand into a desired position.

A slot *c* is formed longitudinally in the handle-bar 5 at the transverse center thereof, said slot having parallel side walls, one end 80 wall of the slot being near the stud-bolt 10 and the opposite end wall so removed therefrom as to afford proper length to the slot for the introduction and rocking adjustment of the cam-block 13. The cam-block 13 is parallel on its sides and of a thickness which permits it to fit loosely in the slot *c*, wherein 85 it is held to rock by the transverse shaft 14.

As shown in Fig. 2, the shaft 14 is journaled in a transverse perforation formed in 90 the side walls of the slot *c* and is therein held to receive rocking adjustment, and to enable the shaft to be manually rocked one end thereof is provided with a knurled head 14^a. The shaft 14 is secured in a transverse perforation 95 in the cam-block 13, so that the block may be rocked when the shaft-head 14^a is manipulated.

The periphery of the cam-block 13 is elliptically spiral, its curved edge constantly increasing in distance from the center of the supporting-shaft 14, and from the point *d* nearest the axis of the shaft to the point *d'* that defines the outer termination of the cam-

face a straight surface may be formed on the cam-block.

A continuous series of teeth *e* is formed on the curved face of the cam-block 13, said 5 teeth being preferably in ratchet form, hooking toward the outer end of the jaw extension 9.

Either of the teeth *e* is adapted to lock upon the transverse corner *e'* on the end wall of the 10 jaw extension 9—that is, on the upper wall defining the loop 9^a—when the selected tooth is disposed opposite said corner by adjustment of the cam-block, and to avoid frictional contact of the teeth *e* with the lower 15 inner corner on the depending loop 9^a said corner is cut away, as shown at *e*² in Figs. 1 and 3.

It will be seen that the range of sliding adjustment which may be given to the jaw 8 is 20 defined by the distance between the farthest tooth *e* and the center of the shaft 14 less the distance of the closest teeth *e* therefrom.

If the adjustment to be given to the jaw 8 requires all the space that can be afforded, the 25 cam-block 13 and shaft 14 are together turned, so as to locate the tooth *e* nearest to the center of the shaft in engagement with the corner *e'*, the jaw 8 being moved at the same time to effect such engagement.

30 Upon application of the spaced jaws 7 8 upon an object to be moved by the wrench when manually operated the instant resistance to retrograde movement had by the jaw 8 is caused by an upward pressure of the tooth *e* next below the one engaged by the corner *e'*, this upward pressure being upon the lower surface of the angular corner *e'*, so that the slideable jaw is held stationary until the wrench-jaws 7 8 are removed from the object with which they were engaged.

It is evident that the sliding jaw 8 may be 40 readily moved toward the fixed jaw 7 and be locked at any point within the range of movement that may be given thereto by turning the shaft 14 in a proper direction.

45 In Fig. 3 a modified means for producing moderate frictional resistance to restrain the sliding jaw 8 from improper movement is

shown and consists in the provision of a plate-spring 15, seated at its ends in shallow recesses *g*, formed in the inner surfaces of the loops 8^a 9^a, the spring being bent so as to impinge its convex side against the handle-bar 5, which will press the upper sides of the loops 8^a 9^a upon the opposite side of the handle-bar, causing friction between said engaged parts, so as to hold the jaw 8 until it is purposely moved.

Having described my invention, I claim as new and desire to secure by Letters Patent— 60

1. The combination with a slotted handle-bar, a fixed jaw thereon, and a slideable jaw, of a peripherally-toothed cam-block held to rock in the slot of the handle-bar, and adapted to have engagement between two adjacent 65 selected teeth thereon, with a corner on the slideable jaw to lock it stationary.

2. The combination with a slotted handle-bar, a fixed jaw at one end of the handle-bar, a slideable jaw having an extension thereon, 70 and means for restraining the free movement of the slideable jaw, of a cam-block held to rotate in the slot in the handle-bar, and teeth on the periphery of the cam-block adapted to interlock with a corner on the free end of the 75 jaw extension.

3. The combination with a slotted handle-bar, a fixed jaw at one end of the handle-bar, a slideable jaw having an extension thereon, 80 and means for restraining the free movement of the slideable jaw, of a spiral-contoured cam-block, loosely engaging within the slot in the handle-bar, teeth on the cam-surface of the block, a transverse shaft journaled in the side walls of the slot and whereon the cam-block 85 is secured near the initial point on the cam-face, and an enlargement on one end of the cam-shaft to facilitate its rocking movement.

In testimony whereof I have signed my name to this specification in the presence of 90 two subscribing witnesses.

ELISHA F. HIRST.
